PIGMENT MIXING APPARATUS

David A. Wallace, Detroit, Mich.

Application December 28, 1936, Serial No. 117,753

7 Claims. (Cl. 259—85)

The present invention relates to material mixing apparatus and in particular provides an improved apparatus for thoroughly mixing previously finely ground paint pigment with a predetermined quantity of a medium or vehicle in the manufacture of paint or other material whereby pigment powders and the like are mixed with a liquid medium.

As will be appreciated from a complete understanding thereof, the improved mixing machine of the present invention may be used to thoroughly mix a wide variety of materials, as well as to reduce a wide variety of materials to a finely ground state. In the specific form illustrated, however, the invention is adapted particularly to the mixing of paint pigment with a suitable medium or vehicle and by way of illustration, but not of limitation, the following description of the invention is concerned with such specific application thereof.

For the purposes of the present description, the manufacture of the paint may be regarded as including four steps, which are first, the refining and reduction to a finely divided state of the paint pigment; second, the mixing of the finely divided pigment with sufficient medium or vehicle to convert it into the form of a stiff paste; third, the grinding of this paste in a suitable machine to thoroughly mix the medium and the pigment and reduce it to a relatively soft and in some instances, to a relatively freely flowing paste; and fourth, the ultimate thinning of the previously mixed material to the proper consistency. The improvements of the present invention are concerned particularly with the third of these steps.

As will be appreciated, the vehicle or medium usually includes an oil such as linseed, or other drying oil, which acts a binder for the pigment and produces a resistant film. On the other hand, the pigment acts to reinforce and strengthen this film as well as, of course, providing the desired color. The quality of the paint depends very largely upon the degree of fineness of the pigment and upon the thoroughness with which the medium is caused to cover and adhere to the entire surface of the individual pigment granules. The third one of the above enumerated four steps is a very important one, accordingly, and a relatively wide variety of grinding and mixing machines have heretofore been proposed for practicing it.

In accordance with the improvements of the present invention, the mixing machine comprises generally two complementary grinding members

between which the material is worked to thoroughly mix it, and in some instances, to further grind the pigment. One of the members is preferably spheroidal in shape and the other of bell or dome shape, fitted over the first member. 5 The cooperating surfaces of one or both of the members are recessed or grooved at one or more points and the previously mentioned relatively thick paste to be acted upon is fed under pressure to the surfaces through these recesses. The 10 two mixing or grinding members are preferably urged into engaging relation to each other under an adjustable fluid or other pressure and as the two mixing members are moved relatively to each other a very thin film of the paste is continuously shaved, so to speak, from the recessed portions and is received between the non-recessed portions of the surfaces thereof, the thinness and uniformity of the film being, of course, promoted by maintaining the edges of the cooperating recesses in a relatively sharp condition and by properly proportioning the pressure exerted.

In further accordance with the present invention, the mixing together and thorough coating of each pigment granule with the vehicle or medium is promoted by the improved movements which are imparted to the two mixing members relative to each other. As illustrated, the members are rotated relative to each other at a continuously or cyclically varying rate, and are also 25 oscillated relative to each other. The paste is preferably introduced between the members adjacent the axial centers thereof and as the mixing progresses, is forced along the surfaces and discharged at the marginal edge of the second 30 or dome-like member, from which point it may be collected by suitable scraping or other collecting mechanism. In addition to effecting a thorough mixing and working of the material, the foregoing structure and combination of motions develops true spherical surfaces on the co-operating parts and maintains these true surfaces until the contacting elements are worn out.

With the foregoing considerations in view, the principal objects of the present invention are to 45 provide a mixing and grinding machine embodying a pair of co-operating grinding and mixing members, between which material to be acted upon may be fed under pressure and which, while retained in co-operative relation under suitable 50 pressure, are moved relatively to each other to effect the mixing or grinding action; to provide such a construction in which the engaging surfaces of one or both of the members are recessed to provide wells into which the material to be 55

acted upon may be fed and out of which the material may be shaved in a uniformly thin layer by the relative motion of the two members; to provide such a construction in which the mixing or grinding members include an inner spheroidal and an outer dome-like member, adapted to be both rotated and oscillated relative to each other; to provide such a construction embodying improved motor driven means for effecting an oscillating movement of the outer member and a rotating movement at a uniformly or cyclically variable rate of the inner member; to provide such a construction in which one of the grinding or mixing members is adapted to be water cooled; to provide such a construction in which the oscillating movement is imparted to the outer grinding or mixing member by means of a continuously rotating shaft and a ball and socket eccentric connection responsive thereto; to provide such a construction in which the drive mechanism for the inner member includes a shaft, and an oscillatable element connected between the shaft and the member for rotating such member at a continuously varying rate; to provide such a construction in which the just stated continuously rotating shaft is of tubular form to receive fluid pressure responsive elements by which the inner mixing or grinding member may be urged into engaging relation to the outer member; to provide such a construction in which the material to be mixed or ground is fed into the outer member at a point adjacent the axial center thereof, is moved by the relative movement between the mixing and grinding members along the surfaces thereof and is discharged from the outer member adjacent the marginal edge thereof; and to provide such a construction in which in different embodiments, the inner and outer mixing or grinding members may be provided with metallic surfaces, stone surfaces, or may be separated by a plurality of ball elements.

With the above as well as other and more specific objects in view, which appear in the following description and the appended claims, preferred but illustrative embodiments of the present invention are shown in the accompanying drawings, throughout which corresponding reference characters are used to designate corresponding parts, and in which:

Figure 1 is a view in elevation, partly in perspective, of a preferred embodiment of the invention;

Fig. 2 is a view in horizontal section, taken along the line 2—2 of Fig. 1;

Fig. 3 is a view in horizontal section, taken along the line 3—3 of Fig. 1;

Fig. 4 is a view taken along the line 4—4 of Fig. 1, but showing only the outer of the two mixing or grinding members;

Fig. 5 is a fragmentary view illustrating a further modification of the invention, in which the surfaces of the inner and outer mixing or grinding members are shown of stone;

Fig. 6 is a fragmentary view illustrating a modified embodiment of the present invention, in which a plurality of balls are interposed between the inner and outer mixing or grinding members;

Fig. 7 is a fragmentary view of a further modification of the present invention, utilizing a plurality of superposed layers of balls between the inner and outer mixing members;

Fig. 8 is a view corresponding generally to Fig. 4, illustrating a modified arrangement of

recesses or wells in the surface of one of the grinding or mixing members;

Fig. 9 is a view corresponding generally to Fig. 4, but illustrating a further modified arrangement of the feed recesses or wells; and

Fig. 10 is a fragmentary view illustrating a modified driving mechanism for the inner of the two mixing or grinding members.

Referring first to Figs. 1 through 4, the machine as a whole may comprise generally an inner mixing or grinding member 20, which is adapted to be driven at a continuously varying rate of speed by a motor 22, though the herein-after described driving mechanism; and an outer mixing or grinding member 24, adapted to be continuously oscillated by a motor 26, through the hereinafter described driving connections. The inner member 20 is provided with an upper surface 28 of spheroidal form, preferably at least hemi-spherical. The outer member 24 is provided with an inner dome-like or spheroidal surface 30, preferably somewhat less than semi-spherical in extent, the engaging surfaces being concentric so that the entire inside surface of the outer member 24 is uniformly spaced from the outer surface of the inner member 20, to thus accommodate a film of uniform thickness. The degree to which the outer member 24 falls short of being hemi-spherical is so proportioned relative to the degree of oscillation imparted thereto, as hereinafter described, that this continuous complete surface cooperation is maintained in all oscillatory positions of the two members 20 and 24 relative to each other.

The material to be mixed or ground in the machine is fed under pressure to the mixing or grinding surfaces of the members 20 and 24 from any suitable external source (not shown) through a conduit 32, which extends through the shank 34 of the outer member 24 and opens into a series of grooves or wells 36, which are cut into the inside surface of the outer member 24 and the edges 36a of which are preferably ground to a sharp condition. A corresponding series of grooves or wells 38 are cut or recessed into the outer surface of the inner member 20. In operation, all of the wells, or recesses, or distributing channels in both the inner and outer members may be expected to be filled with the material to be mixed or ground, and, as the inner and outer members both rotate and oscillate relative to each other, causing the grooves in one member to intersect or pass across those in the other member, a relatively thin film of the material is continuously shaved from the grooves or wells in the two members and is distributed along the ungrooved portions of the surfaces. The grooves or wells in the member 24 may take any of a wide variety of forms, such as the radial fingers 36 shown in detail in Fig. 4, from each of which a plurality of supplemental fingers 36b may extend. Alternatively, the grooves or wells may be simply radially arranged as illustrated at 40 in Fig. 8, or may be spirally arranged as indicated at 42 in Fig. 9. Similarly, corresponding arrangements of the grooves or wells in the inner member 20 may be used, and if desired, one arrangement may be used in the outer member and a different arrangement may be used in the inner member, the particular selection and arrangement of grooves or wells in one or both of the inner and outer members being determined primarily in accordance with the particular material to be ground or mixed in the machine.

The material to be mixed or ground which, as

- previously noted, may enter the machine in the form of a relatively thick paste, after being distributed to the cooperating grinding or mixing surfaces from the wells or grooves, is discharged from the machine in the form of a relatively freely flowing paste at the marginal edge of the outer member 24. The discharged material is permitted to flow by gravity down the vertical side portions 44, and may be collected therefrom in any of a variety of ways. As illustrated, a scraper 46 is provided which engages the portion 44 of the inner member 20 and acts to accumulate the discharged material at one point, thus facilitating its removal. The scraper 46 may be supported on the main machine frame 48 by a bracket 49. Lines 25 and 29 for water or other coolant are connected into the outer member to effect a circulation through a chamber 27 formed therein.
- Considering now the drive mechanism for the outer mixing and driving member 24, the upper end of the member 24 is formed as a ball 50, apertured to define the previously mentioned passage 32, and disposed to be received within a socket 52. Socket 52 in turn is threaded into an eccentric member 54 which is rotatably journaled in a bearing member 56 and held in place therein between locknuts 58 and a shoulder 60 formed in the eccentric 54. The bearing member 56 is suitably secured to a bracket 62 which is pivotally supported as at 64 upon the main machine frame 48, and which also forms a supporting bed for the motor 26. The bracket 62 may be locked in the illustrated operating position by a locking stud 66. In order to afford access to the cooperating surfaces of the inner and outer members 20 and 24 for purposes of inspection or for re-sharpening the edges of the wells or grooves therein, the locking stud 66 may be released, permitting the bracket 62 to be swung bodily in a counter-clockwise direction as viewed in Fig. 1. If desired, the socket 52 may be so formed that the swinging of the bracket 62 carries the member 24 with it. Preferably, and as illustrated, however, the skirt portion 68 of the socket 52 is so formed that the socket 52 may be freely lifted from the ball 50, permitting the member 24 to be separately removed from the inner member 20. To accommodate this separation, a suitable connector 70 may be interposed in the line 32 and dimensioned to pass through the flared opening 72 in the socket 52. The eccentric 54 carries a worm wheel 74, disposed in continuously meshing relation to a worm 76, suitably secured upon the shaft 78 of the motor 26.
- With this arrangement, as will be appreciated, continuous rotation of the shaft 78 effects a corresponding continuous rotation of the eccentric 54, thus causing the socket 52 to travel in a circular path in the plane of rotation of the eccentric. This continuous movement effects a corresponding oscillation of the outer grinding or mixing member over the surface of the inner member 20.
- The drive mechanism for the inner member 20 includes primarily the tubular shaft 80, and the bearing and supplemental driving plates 82, 84 and 86, a ring gear 88, and cooperating pinions 90. The shaft 80 is adapted to be driven continuously by the motor 22, through a worm-wheel 92 carried by the shaft 80 and a worm 94 carried by the shaft of the motor, and is suitably rotatably journaled within the main machine 48 within one or more bearing bushings such as 96. The upper end 98 of shaft 80 projects into an axial bore 100

formed in the inner member 28, and thus determines the axis of rotation of the inner member 20, while allowing the latter to move vertically with respect to the shaft 80 a limited amount, as hereinafter described.

The supplemental driving plates 82 and 84, which are spaced apart to receive between them the non-rotative internal gear 88, are connected together for simultaneous rotation as by a plurality of studs 101 and an aligning pin 102, and are driven in continuous rotation directly by the shaft 80, the lower plate 82 being formed integrally with the later member in the illustrated embodiment. The lower plate 82 is supported on a seat 104 provided therefor in the machine frame 48, a bushing 106 being interposed between these members, and thus acts to provide a thrust bearing for the shaft 80. The internal gear 88, which is supported on the machine frame, is provided with a counter-bore 108, which acts to provide a bearing for the plate 84. Plate 84 in turn provides a rotative bearing for the plate 86, a bushing 110 being interposed between these members. In its lowest position, the member 20 rests directly upon the plate 86, and is drivingly connected thereto for rotation therewith by a plurality of studs 111 and one or more aligning pins such as 112, which permit limited vertical movement of member 20 relative to plate 86.

The driving connection between the plates 82 and 84 and the plate 86 and member 20 is afforded by one or more eccentric pins 114 each received in a slot 116 individual thereto formed in the plate 86 and carried on a trunnion 118 which carries a pinion 90. Each pinion 90 is in continuously meshing relation to the non-rotative ring gear 88, so that it will be appreciated that a continuous bodily rotation of pinions 90 about shafts 80 as an axis, in mesh with the internal gear 88 results in a continuous rotation of eccentrics 114 about the axis of the trunnions 118. These motions of the eccentrics 114 effect a rotation of plate 86 and member 20, which rotation has a continuous uniform component due to the bodily rotation of eccentrics 114 about the axis of shaft 80, and has a second or oscillating component due to the rotation of eccentrics 114 about trunnions 118. The resultant of these two components of motion is a rotation of member 20 at a uniformly or cyclically varying rate.

As previously stated, it is desirable to provide means to maintain the cooperating surfaces 28 and 30 of the members 20 and 24 in cooperative relation to each other at a predetermined and adjustable pressure, to thus govern the thickness of the film of material between them. In the illustrated arrangement, this means is of the fluid pressure type, and comprises a suitable external source of supply 120, connected through a union 122 to a conduit 124 which extends through a union 122 to a conduit 124 which extends through the shaft 80 and opens into the space 126 within the bore 100 above the upper end of the shaft 80, which space thus acts as a piston chamber. With this arrangement, pressure admitted to the chamber 126 through the conduit 124, tends to cause the member 20 to move upwardly relative to the shaft 80, which movement is permitted in view of the slideable connection between these members. Any upward movement of members 20, also separates this member from the adjacent drive plate 86, which separation, however, does not interfere with the driving relation in view of the provision of the drive studs 111. The degree of pressure applied

through the conduit 124, and the pressure applied to the material through conduit 32, of course determines the degree of vertical displacement of the inner member 20 and correspondingly determines the thickness of the film of material interposed between the cooperating grinding or mixing surfaces 28 and 30 of the inner and outer members 20 and 24.

- Considering the operation as a whole of the embodiment shown in Figs. 1 through 4, it will be appreciated that during a grinding or mixing operation, the motors 22 and 26 are continuously driven; that fluid pressure is continuously applied to the conduit 124 through the supply 120 to thereby force the inner and outer members 20 and 24 together with a predetermined pressure, determined by the character of the material to be mixed or ground; and that the material to be mixed or ground is continuously feed into the space between the surfaces 28 and 30 at a suitable externally applied pressure through the supply conduit 32. The wells or recesses 36 and 38 in the cooperating surfaces 30 and 28, respectively, may be expected to be continuously filled with the material to be mixed or ground. The continuously varying rotation of the inner member 20, accompanied by the continuous oscillation relative thereto of the outer member 24 causes the surfaces 28 and 30 to move relative to each other in cyclically varying directions and at cyclically varying rates. During this movement, the movements past each other of the relatively sharp edges of the wells or recesses 36 and 38 causes a thin film of the material to be continuously shaved from the wells or recesses and distributed over the non-recessed portion of the cooperating surfaces 28 and 30. The subjection of this relatively thin film of material to the just mentioned continuously cyclically varying relative movement between the surfaces 28 and 30 thoroughly works the material and is found to insure a thorough coating of each granule of the paste pigment with the medium or vehicle. Depending upon the character or condition of the material at the time it is fed into the machine, the degree of pressure between the cooperating surfaces 28 and 30, the character of the cooperating surfaces 28 and 30, as well as other factors, which will be appreciated by those familiar with machines of the character in question, the action of the machine may consist entirely in a mixing and coating of the individual pigment granules or may consist both in grinding the granules to a finer state and in coating them.
- As the grinding or mixing action progresses, and as the supply of new material is continuously fed into the machine, the material is distributed both by the supply pressure and by centrifugal force away from the axial centers of the cooperating surfaces 28 and 30, and is gradually reduced from a relatively thick paste to a relatively freely flowing paste. The thus completely mixed or ground material is permitted to ultimately discharge from the lower marginal edge of the outer member 24 and downwardly by gravity along the substantially vertical sides 44 of the inner member 20, where it is accumulated by the scraper 46 and is ultimately collected and removed.
- In the arrangement shown in Figs. 1 through 4, it is assumed that the cooperating surfaces 28 and 30 of the inner and outer members 20 and 24 are metallic. Alternatively, as shown in Fig. 5, the members 20 and 24 may be provided with liners 130 and 132 respectively, of stone or other

composition. As in the previous instance, the stones 130 and 132 may be provided with recesses or wells 134 and 136 respectively, within which the material to be acted upon may be received and from which it may be shaved in a relatively uniformly thin layer as previously described.

In the further modified embodiment shown in Fig. 6, a plurality of balls 140 are interposed between the members 142 and 144, which latter members may in all other respects, except those noted below, correspond to the previously described member 20 and 24, respectively. As shown, the work surface 146 of the member 142 is hemispherical and corresponds in all respects to the surface 28 of the member 20 previously described, except that no wells or recesses are required therein. The inner surface of the member 144, on the other hand, is undercut to define a spheroidal recess 148, having the marginal retaining wall 150. Preferably the entire spheroidal recess 148, which preferably corresponds in extent to the previously described surface 30 of the member 24, is completely filled with the balls 140. The material to be operated upon is fed into the space occupied by the balls by suitable external pressure means (not shown) through the conduit 152, and is distributed by the relative motion between the members to the interstices between all of the balls 140. The relative movement between the members 142 and 144 causes the balls 140 to rock in successively different and widely varying directions, which rocking movement, in addition to maintaining the balls 140 in a spherical condition, also works the material in a very effective manner. The completely mixed or ground material is discharged at the marginal edge of the outer member 144 past a gasket 154, and may be collected in the previously described manner by a scraper. In all other respects, a machine embodying the arrangement of Fig. 6 may correspond in all respects to that shown with reference to Figs. 1 through 4.

In the further modified embodiment shown in Fig. 7, the one layer ball arrangement described with reference to Fig. 6, is replaced by a multiple layer ball arrangement, four layers of balls 160 being illustrated as received within a recess 162 formed in the outer member 164. In this embodiment, also, the ball section of the mixing and grinding members is confined to a predetermined portion of the cooperating surfaces, and the remaining portions such as 166 and 168 of these surfaces are arranged as described with reference to the embodiment of Fig. 1, with the exception that the wells or recesses are not required. The mixing or grinding actions are thus effected in two steps, the first step being effected through the action of the balls 160 and the second step being effected through the frictionally acting portions 166 and 168.

It will be appreciated that in the arrangement described with reference to Figs. 1 through 4, due to the limited throw of the eccentrics 114, the inner member 20 normally has a resultant component of rotation in the direction of rotation of the shaft 80, the rate of the oscillating component being lower than the rate of the component imparted directly by the shaft 80. This relation is a fixed one in the arrangement of Fig. 1 in view of the fact that the internal gear 88 is non-rotatably supported.

In the modified embodiment of Fig. 10, the previously described non-rotative mounting for the internal gear is replaced by a rotative mounting therefor and the gear 88 is provided with an

external set of teeth 170, through which it may be driven at a desired rate through a drive pinion 172. The drive pinion 172 is suitably journaled in the main machine 48, and may be driven at a suitably adjustable rate through any suitable external source of power illustrated as a pulley 174 and drive belt 176. The rotation of gear 88 in timed relation to and during the rotation of the shaft 80, as will be appreciated, changes the 10 rate of the oscillating component of movement imparted to the member 20 through the eccentric 114. By providing this range of adjustment, it will be appreciated that the oscillating component may be varied relative to the main 15 rotative component from a very small ratio to one at which the member 20 advances in a series of step by step movements and also to one in which the member 20 actually oscillates instead of rotating continuously in one direction. In all other respects except the driving connection for the ring gear 88, the embodiment of Fig. 10 preferably corresponds to that described with reference to 20 Figs. 1 through 4.

Although specific embodiments of the invention have been described, it will be appreciated that various modifications in the form, number, and arrangement of parts may be made therein within the spirit and scope thereof.

What is claimed is:

30 1. In a machine of the class described, an inner member having a spheroidal portion formed at the end thereof, an outer member having a spheroidal portion adapted to be fitted over said first portion, said inner and outer members being adapted to receive a film of material to be operated upon between them, means for effecting axial rotation of said inner member at a continuously varying rate, and additional means for effecting an oscillation of said outer member 35 about said inner member, to thereby work said material.

2. In a machine of the class described, an inner member having a spheroidal portion formed at the end thereof, an outer member having a spheroidal portion adapted to be fitted over said first portion, said inner and outer members being adapted to receive a film of material to be operated upon between them, at least one of said surfaces having a material receiving well formation therein, means for introducing material to said well formation adjacent the axial center of the associated surface, and means for oscillating one of said surfaces and for rotating the other surface at a continuously varying rate to cause said material to work out of said well formation and distribute over the cooperating surfaces.

3. In a machine of the class described, an inner member having a spheroidal portion formed at the end thereof, an outer member having a spheroidal portion adapted to be fitted over said first portion, said inner and outer members being adapted to receive a film of material to be operated upon between them, means for introducing material between said surfaces, and means for effecting rotation and oscillation of one of said members and for causing rotation at a continu-

ously varying rate of the other number to cause said material to work from said well formation and distribute over said cooperating surfaces.

4. In a machine of the class described, an inner member having a spheroidal portion formed at the end thereof, an outer member having a spheroidal portion adapted to be fitted over said first portion, said inner and outer members being adapted to receive a film of material to be operated upon between them, at least one of said 10 surfaces having a material receiving well formation therein, means for introducing material to said well formation adjacent the axial center of the associated surface, means for effecting axial rotation of said inner member at a continuously 15 varying rate, and means for effecting oscillation of said outer member to thereby cause said material to work out of said well formation and distribute over said surfaces.

5. In a machine of the class described, an inner 20 member having a surface of spheroidal form formed at one end thereof, an outer member having a surface of spheroidal form and adapted to fit over said first surface, said surfaces being adapted to receive between them a film of material to be worked, a continuously rotating shaft, 25 means for translating the continuous rotation of said shaft into oscillating movement of said outer member, a second continuously rotating shaft, and means interposed between said second shaft 30 and said inner member for causing continuously varying axial rotation of said inner member in response to the rotation of said second shaft.

6. In a machine of the class described, an inner member having a surface of spheroidal form 35 formed at one end thereof, an outer member having a surface of spheroidal form and adapted to fit over said first surface, said surfaces being adapted to receive between them a film of material to be worked, a continuously rotating shaft, 40 means for translating the continuous rotation of said shaft into oscillating movement of said outer member, a second continuously rotating shaft, and intermediate gearing including a non-rotative gear and an eccentric element responsive 45 thereto for causing continuously varying rotative movement of said inner member in response to rotation of said second shaft.

7. In a machine of the class described, an inner member having a surface of spheroidal form 50 formed at one end thereof, an outer member having a surface of spheroidal form and adapted to fit over said first surface, said surfaces being adapted to receive between them a film of material to be worked, a continuously rotating shaft, 55 means for translating the continuous rotation of said shaft into oscillating movement of said outer member, a second continuously rotating shaft, intermediate gearing interposed between said second shaft and said inner member including a rotatable gear and an eccentric element 60 responsive thereto for causing continuously varying rotative movement of said inner member in response to rotation, and means for rotating said gear.

DAVID A. WALLACE.

CERTIFICATE OF CORRECTION.

Patent No. 2,179,970.

November 14, 1939.

DAVID A. WALLACE.

It is hereby certified that error appears in the printed specification of the above numbered patent requiring correction as follows: Page 3, second column, line 13, for the word "later" read latter; line 31, for "plpate" read plate; line 39, for "shafts" read shaft; lines 60 and 61, strike out the words "which extends through a union 122 to a conduit 124"; page 5, second column, line 1, claim 3, for "number" read member; and that the said Letters Patent should be read with this correction therein that the same may conform to the record of the case in the Patent Office.

Signed and sealed this 19th day of December, A. D. 1939.
